UNITED STATES PATENT OFFICE.

JOHN N. HELTZEL, OF WARREN, OHIO, ASSIGNOR TO THE HELTZEL STEEL FORM & IRON CO., OF WARREN, OHIO.

CONCRETE-MOLD-FORM STAY.

1,345,179.

Specification of Letters Patent. Patented June 29, 1920.

Application filed October 4, 1919. Serial No. 328,469.

To all whom it may concern:

Be it known that I, JOHN N. HELTZEL, a citizen of the United States, residing at Warren, in the county of Trumbull and 5 State of Ohio, have invented a new and useful Concrete-Mold-Form Stay, of which the following is a specification.

This invention relates to molding apparatus and more particularly to portable and 10 adjustable concrete form stays.

The primary object of the invention is to provide a means for adjustably and removably supporting the side walls of the concrete form to permit the same to be used 15 in connection with concrete structures requiring various heights.

A further object of the invention is to provide means carried by the stay for restricting the movement thereof when the 20 same is being driven into the ground surface on which the mold is being set up.

With the foregoing and other objects in view which appear as the description proceeds, the invention resides in the combination and arrangement of parts and in the 25 details of construction hereinafter described and claimed, it being understood that changes in the precise embodiment of the invention herein disclosed, may be made 30 within the scope of what is claimed without departing from the spirit of the invention.

Referring to the drawings:

Figure 1 illustrates a side elevational view of the stays and concrete form supported 35 thereby, one end of the form being broken away.

Fig. 2 illustrates a sectional view taken on line 2—2 of Fig. 1, and

Fig. 3 is a top plan view of a stay with 40 the adjustable bracket positioned thereon.

Referring to the drawings in detail, reference character 5 designates a stay including right angle flange members 6 and 7, the lower ends of said flange members 6 and 7 45 being tapered to form the pointed end 8, to facilitate the driving of the stay into the ground surface on which the mold is to be assembled.

Disposed directly above the pointed end 50 8 of the stay is a brake, in form of a right angled plate, including flanges 9 and 10, the flange 9 thereof being secured to the flange 6 by means of rivets 11 passing through suitable openings provided in the 55 flanges 6 and 9.

As shown, the flange 10 extends at right angles with relation to the flange 9, and is relatively wide to engage the ground surface when the stay is driven into the ground, to prevent or restrict the movement of the 60 stay into the ground, to prevent the stay from being driven too far, and to insure a relative height of the various stays used in the mold construction.

The flange 6, which when positioned 65 forms the rear flange of the stay, has its rear edge provided with notches as shown at 12, the distance between the notches varying to provide various heights and adjustments for the bracket 13 to be more fully 70 described.

Employed with each of the stays, is a removable bracket member 13 which is curved downwardly as at 14, the lower extremity thereof terminating in an upwardly extending hook member 15, to receive the downwardly extending flange 16 of the concrete form 17.

As shown by Fig. 3 of the drawing, the bracket member 13 is provided with a substantially L-shaped notch or slot 18, the portion 19 thereof being wider than the width of the flange 7, over which the same operates, to permit the bracket, when positioned on the stay, to fall down into a position to 80 closely engage the flange 7 of the stay, and at the same time permit the bracket to be moved upwardly in order that the bracket may be moved from the notch in which the same is engaging, to another position of adjustment.

The concrete form 17, forming a part of the invention includes a body portion 18', which when in position lies at right angles with relation to the flange 7 of the stay, the upper 95 end 19' thereof extending at right angles to the body portion 18', the extreme edge of said right angle portion 19 extending at right angles thereto and lies in a position to engage within the hook member 15 of the 100 bracket 13.

The lower extremity of the body 18' also extends at right angles as at 20, and has its extreme edge extending upwardly as at 21 to closely engage the flange 7 of the stay in 105 order that the same will be held in its horizontal position, against displacement.

In operation, the stays 5 are positioned in the ground surface until the brakes, secured thereto engage the ground surface to 110

prevent the stays from being positioned too far into the ground surface, and to insure uniformity in the heights of the stays.

The bracket members 13 are now positioned in the proper notches of the stays, which of course are regulated according to the height of the structure to be formed, and the form positioned on the hook portions of the bracket members 13.

10 The concrete in plastic form is then poured in between the forms, and allowed to set until the concrete hardens, whereupon the forms are removed.

It is to be understood that the invention 15 as shown, includes only one side of a concrete mold, but it is of course obvious that two of such structures are positioned in spaced relation with each other to form the opposite sides of the mold, to permit the plastic concrete to be positioned therebetween.

Having thus described my invention, what I claim is:—

1. In a portable mold, stays including an angle irons, one of the walls of each of said stays having notches, a bracket member positioned on each of the stays, said bracket member having a substantially L-shaped slot formed therein, and adapted to embrace the stay, one of the walls of said L-shaped slot coöperating with the notched walls of the stay for holding the bracket in various positions of adjustment, and means on one end of said bracket for securing a concrete form thereto.

2. In a portable mold, stays, each of said

stays being provided with a notched portion, a bracket supported on each of these stays, a concrete form removably supported by the bracket, and means carried by the stay for 40 restricting movement thereof into the ground surface on which the mold is supported.

3. In a portable mold, stays, each of said stays having a plurality of notches formed 45 along one of the edges thereof, a bracket having a slot embracing the stay, one of the walls of said slot coöperating with the notches, and means carried by the stay for restricting movement thereof into the 50 ground surface, on which the mold is supported.

4. In a portable mold, stays, each of said stays being provided with a notched portion, a bracket supported by each of the 55 stays, each of said stays having a slotted portion embracing the bracket, one of the walls of said slotted portion coöperating with the notches for supporting the bracket in various positions of adjustment, and said 60 bracket being curved downwardly to set up a binding action between the bracket and stay, and a movable form supported by the bracket.

In testimony that I claim the foregoing as 65 my own, I have hereto affixed my signature in the presence of two witnesses.

JOHN N. HELTZEL.
